APPARATUS FOR APPLYING METAL STRAPS

Roy F. McMahan, Avondale, near Louisville, Ky.

Original application October 15, 1938, Serial No. 235,129. Divided and this application April 1, 1942, Serial No. 437,301.

7 Claims. (Cl. 1—11)

This invention relates to improvements in apparatus for applying a metal binding-strap to wooden members, and is a division of my earlier application, Serial Number 235,129, filed October 15, 1938, and entitled "Metal bound box."

In the aforesaid application, there is disclosed a wood box having a metal binding-strap engaging one face of each of the respective box sections. The strap is provided with a plurality of teeth, struck therefrom and integral therewith, and each tooth has a flat shank extending through its respective box section. The free-end portion of each tooth is folded against the opposite face of the respective box section, and arched longitudinally throughout the length thereof so that the end edge of the tooth is curled into the respective box section; reenforcing means is formed in the arched free-end portion of each tooth for securing the same in its folded position against the opposite face of the respective box section. Therefore, it is the object of this invention to provide a simple and effective apparatus for applying such a metal binding-strap to the respective sections of a box.

Another object of this invention is to provide a simple tool that is mounted upon a conventional power-driven punch-press, much in the same manner as a conventional forming die, for applying the said strap to the respective sections of a wood box.

Also, it is a further object of this invention to provide apparatus for applying a metal-binding strap to articles other than the wood box illustrated in my aforesaid application.

These and other objects will be apparent to those skilled in the art as the following description is read in connection with the accompanying drawings, in which:

Figure 1 is a perspective view of a box having a metal binding-strap applied by the apparatus disclosed in this invention;

Figure 2 is an enlarged partial view of the corner of the box illustrating teeth 9 and 10 pressed through their respective box sections, and also showing the relation of the corner-protecting members 8f and 8g before the free-ends of same are secured to the corresponding box sections;

Figure 3 is a partial view showing the outer face of the binding-strap that lies along side 2 of the box;

Figure 4 is a partial view showing the outer face of the binding-strap that lies along end 4 of the box;

Figure 5 is an end view of the binding-strap showing the corner protecting members 8f and 8g before the same are secured to the corresponding side and end of the box;

Figure 6 is a partial sectional-view of the binding-strap showing the construction and relation of the short teeth 10 that are pressed through the relatively thin side members of the box, and long teeth 9 that are pressed through the relatively thick end members of the box;

Figure 7 is a partial sectional view taken along lines 7—7 of Figure 2 showing the shape of the corner protecting member 8f after same is secured to its corresponding box member;

Figure 8 is a partial vertical sectional-view showing the preferred construction of the apparatus employed to apply the metal binding-strap to a box, and illustrating the teeth 10 of the strap pressed through box members 1 and 2;

Figure 9 is also a partial vertical sectional-view illustrating the strap-applying apparatus substantially beginning with the step of bending the teeth 10 and corner protecting members 8g into approximately arch-shape;

Figure 10 is likewise a partial vertical sectional-view illustrating the strap-applying apparatus substantially completing the arch forming operation required to curl the free-end edges of each tooth, and the free end edge of each end-protecting member into their respective box sections, and substantially beginning the forming of the reenforcing bead 9c in the arched free-end portion of each tooth.

Figure 11 is an enlarged partial elevational view of one of the tooth forming tools as viewed along lines 11—11 of Figure 9;

Figure 12 is an enlarged end view of one of the tooth forming tools;

Figure 13 is a partial sectional view showing the final shape of a tooth in secured relation with its corresponding box member;

Figure 14 is a partial sectional view taken along lines 14—14 of Figure 13 showing the reenforcing bead 9c formed in the arched free-end of each tooth; and

Figure 15 is a partial vertical sectional view illustrating the strap applying apparatus in normal condition, that is, the relation of the various parts after the press is loaded and before the press is operated. Figure 15 also shows guide pins P and limit stops S holding the pressure plate 14 in functional relationship with its associated parts, and the manner in which the die 11 is associated with the head or ram of a power press.

In the foregoing drawings, only vertical sectional-views of the forming tools are presented, as it is believed that these are the essential views required to gain a thorough understanding of the invention. As illustrated in Fig. 15, it is to be understood that the tool holder 11 is provided with a suitable mounting means so that the same is fixedly secured to the reciprocating slide of a conventional power-driven punch-press, for vertically reciprocating the same relative to a stationary table T that is fixedly secured to the stationary bolster plate of a conventional power press. Therefore, it is to be understood that the metal binding-strap 8 rests upon the table T while the reciprocating forming tool consisting of pressure plate 14 and forming tools 12, etc., is moved downwardly into engagement with the respective box members and the teeth of the binding-strap.

The specific apparatus illustrated in the drawings, is primarily employed to secure a sheet-metal binding-strap to the respective sections of a wood box. However, it will be apparent that the teachings of this invention may be utilized to secure metal binding-straps to various kinds of articles. Accordingly, it is important to observe the relation existing between the inner faces of the arched ends of the forming tools 12 and the outer faces of the teeth that are engaged by the respective forming tools.

For the specific relation between the various parts of the forming tool, reference is directed to the drawings.

Thus, in specifically describing the particular embodiment of my strap-applying tool, I do not desire to be limited other than by the scope of the appended claims. Therefore, although the forming tool includes depending arms 161 and arched contours 18 for securing the end-protecting members 8g to their respective box members, it is to be understood that these may be altered or omitted, without affecting the operation of the pressure plate 14 and forming tools 12. Thus, for a more complete understanding of the parts utilized in securing the end-protecting members 8g, reference is made to my earlier United States Patent Number 2,253,639, issued August 26, 1941, and entitled "Bending die"; also for a more complete understanding of the method utilized in securing these end-protecting members to their respective box sections reference is made to my earlier United States Patent Number 2,201,193, issued May 21, 1940, and entitled "Hanger and method of attaching same."

In Figure 1 of the drawings, a box is shown having metal binding-straps 8 secured to the respective sections of the box by means of the strap-applying tools forming the primary object of this invention. It will be observed that the box is preferably constructed from five pieces of relatively thin timber, or similar material, to form the side members 1 and 2, end members 4 and 5, and bottom member 3. It will also be observed that all of these box members are rigidly and permanently secured together by two metal binding-straps 8 of specially constructed angle-section.

Each face of these angled binding-straps has a series of teeth struck therefrom, which teeth are adapted to be pressed into and through juxtaposed faces of the box members, for rigidly and permanently securing the same together without the use of nails, screws, battens, or other similar securing means. With particular reference to Figures 1 to 7 inclusive, it will be ob-

served that the teeth along each face of the binding-strap have a triangular shape and project substantially at right angles from the corresponding face thereof in substantially a flat plane. In this respect, particular emphasis is made of the fact that the plane of each tooth is made to register with the grain of the timber forming the side, end and bottom members of the box. This construction and arrangement is clearly shown in Figure 1. The object of this arrangement is not only to facilitate assemblage, but to provide the least possible fracturing of the fibres of the timbers so as to afford the greatest mechanical strength. This arrangement further minimizes rejects because of split timbers that would otherwise be encountered by not having the plane of the teeth substantially parallel with the grain of the timbers. This arrangement further enables the teeth to be pressed into and through the box members with the least possible disturbance to their free projecting positions, thus assuring proper alignment of the teeth with their corresponding forming or clinching tools, hereinafter described.

In arranging the box members prior to being assembled into the box illustrated in Figure 1, two specially constructed angled binding-straps of the required length and gage are provided, each strap having a series of teeth struck from each of its faces and substantially uniformly spaced throughout its length. The particular relation of each tooth, one to the other and to the grain of the timber, is clearly shown in Figure 1.

In assembling the binding-straps with the box timbers, the two straps are laid parallel on a stationary table T of a conventional power press, and the sides 1, 2 and bottom 3 laid flat-wise upon the upstanding free-ends of the teeth projecting from the corresponding faces of the straps, which relationship is shown in Fig. 15. The power press is then operated, and the reciprocating forming tool consisting of tool holder 11 and pressure plate 14 moves downwardly towards the box timbers. The pressure plate 14 engages the timbers and presses the same downwardly so that the upstanding teeth 10 are pressed into and through the box timbers, observe Figures 1, 2, 8, 9, 10, 13 and 14. Each side member 1 and 2, and the bottom member 3 are spaced, and the upright face of each strap is formed with a V gap or mitre adjacent each junction of a side and bottom member so that the box members can be subsequently folded to assume the position illustrated in Figure 1.

Referring now to Figures 8 to 12, and 15, it will be observed that the tool for pressing the teeth 10 into and through the box timbers, and for subsequently clinching same, comprises a series of forming tools 12 carried by a die block 11, and a pressure plate 14 normally biased away from the die block 11 by suitable springs 12s disposed between the die block 11 and pressure plate 14.

Thus, it will be apparent that the pressure plate 14 shown in Figures 8, 9, 10 and 15, first contacts the box members 1, 2 and 3, and presses the teeth 10 into and through same by force from the power press transmitted to the said plate through the springs 12s, which springs are sufficiently strong to effect penetration. As illustrated in Figure 8, each forming tool 12 engages its corresponding tooth 10 after the box member is pressed against the respective inner face of the binding-strap.

Particular attention is directed to the shape and construction of each forming tool 12. Each forming tool 12 is preferably cylindrical in shape and it will be observed that the end of each tool 12 has a concaved arcuate contour 12b, and an arcuate beading rib 12c located centrally of the lower face of the forming tool 12. Note Figures 11 and 12.

Thus, each arcuate beading-rib 12c engages the free-end of a tooth 10 in its downward movement, and progressively rotates, or curls, the free-end in the manner illustrated in Figures 8, 9 and 10, until the final position illustrated in Figures 13 and 14 is reached. Just prior to each tooth reaching its final position, the resistance of the compressed box member increases, and exerts sufficient pressure to permit the beading-rib 12c of each tool to form a reenforcing bead in the curled end of each corresponding tooth, as illustrated in Figures 13 and 14.

It is important to note that my strap-applying apparatus provides a slight shearing of the fibres of the box timbers adjacent the inner faces of the box members, so that each tooth is independently and simultaneously curled to a position below the inner face of the box members. This arrangement eliminates objectionable metallic projections within the box that may otherwise injure the hands of those required to handle the box.

Thus, with a single stroke of a conventional power press, the side and bottom members of the box are secured to the corresponding faces of the binding-straps.

In Figures 1, 2, 5 and 7 to 10, inclusive, it will be observed that each end of the binding-strap 8 is provided with corner protecting and end securing members 8f and 8g. These members are each curled around the edge of the corresponding box timbers, and their free-ends driven into the corresponding member. Note Figure 7 which particularly illustrates the member 8f curled into the respective box section 4.

With reference to Figures 8 to 10 inclusive, it will be observed that I have provided arcuate faces 18, guides 162 and projections 19 for arching the members 8g, or 8f, in accordance with the teachings of my aforesaid earlier Patents Numbers 2,253,639 and 2,201,193. It will also be observed that the face 19a between the arched contours 18 is depressed, not only to provide the required projections 19 for penetrating the surface of the box member to provide the final securing operation for the members 8g, but sufficient to provide a recess into which the pressure plate 14 moves during the operation of the tools 12 upon the free-ends of the teeth 10.

As illustrated in Figure 12, the pressure plate 14 is provided with a series of round apertures through which the respective forming tools 12 operate. It will also be noted that each tool 12 has a flat portion 12a, and it is to be understood that each tool 12 is secured to the die block 11 by set screws 15, as illustrated in Figure 11.

It is also to be understood that the pressure plate 14 is provided with guide pins P and limit stops S so that the same is normally held in a position relative to the forming tools 12 as shown in Fig. 15. Obviously, such expedients are well known to those skilled in the art, and it is not regarded necessary to elaborate upon their construction and relation. It is to be understood that the construction and arrangement of the guide pins and limit stops for the pressure plate 14 may take various forms without departing

from the spirit of this invention, since the essential novelty of this invention resides in the construction of the forming tools 12, the relation of these tools relative to the teeth 10, and the use of the tools 12 in combination with the arcuate contours 18. Accordingly, it is believed that Figs. 8 to 12 and 15, sufficiently illustrate the invention so that those skilled in the art may practice the same.

Therefore, while I have described and illustrated the construction and relation of the tools required to secure the binding-strap 8 to the sides and bottom of the box, it is believed that it will be apparent to those skilled in the art, the required arrangement of the tools to secure the straps 8 to the respective ends of the box.

Thus, after the strap is secured to the side members 1 and 2, the side members are bent upright at the mitre joints as illustrated in Figure 1. The end members 4 and 5 are then placed within the partially constructed box, either separately or together, and subjected to the action of suitable tools, made in accordance with the teachings of those described for the side and bottom members, for curling the teeth 9 into the respective ends of the box and forming the reinforcing means 9c in the arched ends thereof, as shown in Figures 13 and 14. In this respect, it is to be understood that the tools for the ends of the box are also provided with the required arcuate contours 18, projections 19 and arms 161, for curling the end protecting-members 8f as shown in Figure 7.

While I have shown and described what I consider to be the most practical embodiment of my invention, it is to be understood that various changes in construction may be made under the scope of the appended claims.

Having thus described my invention, I claim:

1. In apparatus for applying a metal binding-strap having a plurality of fastening projections formed integrally therewith to a wooden member; a plurality of forming tools, one for each fastening projection, each tool having on its forming end a semi-circular concave-face; a pressure plate operatively associated with the said forming tools; means for moving the pressure plate against the said member to press simultaneously the said fastening projections into and through the same; means for longitudinally moving each forming tool against its respective fastening projection, to curl it into substantially arch shape and to force the free end thereof into the opposite face of the said member; and means operatively associated with each forming tool for longitudinally denting the curled portion of each corresponding projection so as to re-enforce the said fastening projection in its curled condition.

2. In apparatus for applying a metal binding-strap having a plurality of fastening projections formed integrally therewith to a wooden member; a plurality of forming tools, one for each fastening projection, each tool having on its forming end a semi-circular concave face having the plane of the extremity of its concave face substantially parallel with the plane of the extremity of the corresponding fastening projection, each tool also having a convex rib extending circumferentially of its concave face; means for longitudinally moving each tool against its respective fastening projection, to curl it into substantially arch shape and to form a concave re-enforcing bead longitudinally therein.

3. In apparatus for applying a metal binding-

strap having a fastening projection formed integrally therewith to a wooden member; means for longitudinally moving a forming tool having on its forming end a semi-circular concave face, a convex rib extending circumferentially of said face and an end edge of the concave face positioned just outside the projecting end of the said projection; and means for guiding the forming tool against the said projection to curl it into an approximately arch-shaped clinched-end, force the free-end thereof into the wooden member, and to form a concave re-enforcing bead longitudinally of said clinched end.

4. In apparatus for applying a metal binding strap having a fastening projection formed integrally therewith to a wooden member, means for longitudinally moving a forming tool having on its acting end a semi-circular concave face and a convex rib extending circumferentially of said face, and means for guiding said forming tool against said projection to curl it into substantially arch-shape and to form a concave re-enforcing bead longitudinally therein.

5. In apparatus for applying a metal binding strap having a plurality of fastening projections formed integrally therewith to a wooden member; a plurality of forming tools, one for each fastening projection, each tool having on its forming end a semi-circular concave-face, a convex rib extending circumferentially of the concave face and an end edge of the concave face positioned above and just outside of the projecting end of the corresponding fastening projection; a pressure plate operatively associated with the said forming tools; means for moving the pressure plate against the member to press simultaneously the said fastening projections into and through the same; means for longitudinally moving each

forming tool; and means for guiding each forming tool against its corresponding fastening projection to curl it into substantially arch-shape, force the free-end thereof into the opposite face 5 of the wooden member, and to form a concave re-enforcing bead longitudinally of the arched end.

6. In apparatus for applying a metal binding strap having a fastening projection formed integrally therewith to a wooden member; a forming tool having on its forming end a semi-circular concave-face and a convex rib extending circumferentially of the said face; a pressure plate operatively associated with the said forming tool; means for moving the pressure plate against the member to press simultaneously the said fastening projection into and through the same; means for longitudinally moving the forming tool; and means for guiding the forming tool against the 15 said projection to curl it into substantially arch-shape and to form a concave re-enforcing bead longitudinally therein.

7. In apparatus for applying a metal binding strap having a fastening projection formed integrally therewith to a wooden member; a forming tool having on its forming end an arched concave face for curling the projection longitudinally into substantially arch-shape, and means for bending the arched projection laterally to reinforce the same in its arched condition; means for longitudinally moving the forming tool and means for guiding the forming tool against the free end of the said projection to curl the projection into substantially arch-shape and to bend the arched projection laterally to re-enforce the 20 same in its arched condition.

ROY F. McMAHAN.
